UNITED STATES PATENT OFFICE

DEWITT TAPPAN, OF ROCHESTER, NEW YORK, ASSIGNOR TO E. C. BROWN COMPANY, OF ROCHESTER, NEW YORK

DESIGN FOR A JAR

Application filed December 11, 1930. Serial No. 37,939. Term of patent 14 years.

To all whom it may concern:

Be it known that I, DEWITT TAPPAN, a citizen of the United States, residing at Rochester, in the county of Monroe and State of New York, have invented a new, original, and ornamental Design for a Jar, of which the following is a specification, reference being had to the accompanying drawings, forming a part thereof.

And, Fig. 2 is an end view of the jar.
I claim:

The ornamental design for a jar, as shown.

DEWITT TAPPAN.
